US0D1012298S

(12) **United States Design Patent** (10) **Patent No.:** **US D1,012,298 S**
(45) **Date of Patent:** **** Jan. 23, 2024**

(54) **WAIST SHAPER**

(71) Applicant: **FAJAS MYD POSQUIRURGICAS S.A.S.**, Medellín (CO)

(72) Inventor: **Aleida María Gómez Cataño**, Medellin (CO)

(73) Assignee: **FAJAS MYD POSQUIRURGICAS S.A.S.**, Medellín (CO)

(**) Term: **15 Years**

(21) Appl. No.: **29/797,326**

(22) Filed: **Jun. 30, 2021**

(30) **Foreign Application Priority Data**

Mar. 31, 2021 (CO) NC2021/0004099

(51) **LOC (14) Cl.** **24-02**

(52) **U.S. Cl.**

USPC **D24/190**

(57) **CLAIM**

The ornamental design for a waist shaper, as shown and described.

DESCRIPTION

FIG. 1 is right-side perspective view of a waist shaper, showing my new design;

FIG. 2 is a front perspective view of the waist shaper;

FIG. 3 is a front view of the waist shaper;

FIG. 4 is a back perspective view of the waist shaper;

FIG. 5 is a second front perspective view of the waist shaper;

FIG. 6 is a top view of the waist shaper; and,

FIG. 7 is a rear view of the waist shaper.

The broken lines show portions of the waist shaper that form no part of the claimed design.

1 Claim, 7 Drawing Sheets
